IMAGE STORAGE TUBE

Bernard C. Gardner, Waltham, Mass., assignor to
 Raytheon Manufacturing Company, Newton,
 Mass., a corporation of Delaware

Application December 18, 1948, Serial No. 66,083

22 Claims. (Cl. 313—89)

1

This invention relates to electron tubes of the kind wherein an image can be stored in the form of an electrical charge pattern, and in particular to a tube having great flexibility of use.

It is an object of the invention to provide an image storage tube wherein an image can be recorded at any desired rate of speed within wide limits, stored for a great length of time and examined repeatedly without appreciable loss of definition.

It is another object of the invention to provide such a storage tube wherein the stored image can be removed rapidly when desired.

It is another object of the invention to provide such a tube which has high resolving power, and can consequently record and store an image having a great many elements of information.

It is still another object of the invention to provide an image storage tube wherein the stored image has a large dynamic range of intensities.

The foregoing and other objects and features of the invention will be appreciated from the detailed discussion of certain embodiments thereof that follows, reference being had to the accompanying drawings wherein:

Fig. 1 illustrates, partly in vertical section, a tube in accordance with the invention in a circuit which is shown schematically;

Fig. 2 illustrates the storage element of the tube of Fig. 1 in cross-section, greatly enlarged, cooperating with an electron beam;

Fig. 3 illustrates, partly in vertical section, another tube constructed in accordance with the invention;

Fig. 4 illustrates schematically an erasing circuit for the tube of Fig. 3;

Fig. 5 illustrates schematically a writing circuit for the tube of Fig. 3;

Fig. 6 illustrates schematically a reading circuit for the tube of Fig. 3;

Fig. 7 is a diagrammatic view, greatly enlarged, illustrating the operation of the tube of Fig. 3;

Fig. 8 illustrates, partly in vertical section, a third tube in accordance with the invention;

Fig. 9 illustrates schematically a writing and/or erasing circuit for the tube of Fig. 8;

Fig. 10 illustrates a reading circuit for the tube of Fig. 8; and,

Fig. 11 illustrates a modification of the tube of Fig. 8.

In general, the present invention contemplates the employment of a perforated conducting screen electrode which is coated on one side with a non-conductive material functioning as a storage element, writing being accomplished by scanning

2

the dielectric coated side of the screen, and reading being accomplished by scanning the uncoated side of the screen. Such a screen electrode, as employed herein, may also be termed a "target."

5 The charge pattern on the coated side of the screen determines the current that flows to a collector electrode which is suitably positioned with relation to the storage screen. The charge pattern controls the passage to the collector electrode of secondary electrons formed when a high voltage reading beam strikes the uncoated side of the screen, or of a low voltage reading beam directly.

Referring now to Fig. 1, the tube there shown 15 comprises an envelope 10 of glass, or the like, having at the right hand end a first electron gun 11 which is employed for writing and erasing purposes, and at the left hand end a second electron gun 12, which is employed for reading purposes.

The first gun 11 includes a cathode 13, a control grid 14 and a focusing and accelerating anode 15. A deflection coil system 16 is suitably placed around the neck of the tube at the right hand end to cooperate with the first gun

25 11. A high voltage accelerating and scavenging electrode 17 is coated on the inside of the envelope 10 in front of the first gun 11. This high voltage electrode may be made of a suspension of colloidal carbon known as "Aquadag."

The second electron gun 12 includes a cathode 21, a control grid 22, and a focusing and accelerating anode 23. A second set of deflection coils 24 is suitably disposed around the left hand end of the tube to cooperate with the second gun 12

35 for the purpose of deflecting the beam produced thereby. A second high voltage and scavenging electrode 25 is coated on the inside of the envelope 10, covering substantially all the left hand half of the envelope in front of the second gun 12. The second high voltage electrode 25 is constructed similarly to the first high voltage electrode 17.

A storage screen 26 is disposed transversely in the envelope 10, at about the center portion thereof. This screen, which is shown greatly enlarged in Fig. 2, comprises essentially a thin sheet of metal 27, which may, for example, be a nickel plate of a thickness 0.0005 inch, coated on one side with a dielectric 28 of similar thickness.

45 50 The composition of the dielectric will be discussed in detail below. The plate 27 is provided with square holes 30, of which there are about 400 to the inch along the surface of the plate. Each hole 30 is initially about 0.0015 inch square, so that the uncoated screen is about 36 per cent

open. In the process of applying the dielectric coat 28, the holes 30 are reduced somewhat in size so that the finished storage screen 26 is about 28 per cent open. It has been found that a storage screen which is as low as 16 per cent open, corresponding to a hole size of 0.0010 inch square, can be employed satisfactorily. As is shown in Fig. 2, the size of the holes 30 and their spacing along the storage screen are such that an electron beam 33, impinging upon the storage screen, will simultaneously cover approximately six of the holes 30, when the beam has a diameter of approximately 0.020 inch. Such a beam is termed a "six-element beam." As will become apparent below, beams as narrow as 0.010 inch in diameter are suitable and desirable for use in tubes of the invention. The beam that is illustrated in Fig. 2 is so disposed with relation to the storage screen 26 that it may be considered to be a reading beam.

Referring again to Fig. 1, a collector electrode 35 is coated on the inside of the envelope 10 in the form of an annulus disposed between the storage screen 26 and the high voltage anode 17 of the first gun 11. The arrangement of elements is such that a charge pattern can be placed upon the dielectric coating 28 of the storage screen 26 by a beam from the first gun 11, and this storage pattern can influence the passage of electrons either primary or secondary originating from the reading beam of the second gun 12 to the collector electrode 35. Circuits for accomplishing the various desired functions of the tube will now be discussed.

Erasing

Erasing of any prior stored information or any prior stored charge pattern on the dielectric 28 is accomplished by flooding the screen 26 with slow electrons from the first gun 11 of a potential so low that the number of secondary electrons leaving the screen is fewer than the number of primary electrons arriving thereat. As is well known, when electrons strike a body, be it conductive or non-conductive, secondary electrons are caused to be emitted from the body. Depending upon the velocity with which the striking electrons, known as primary electrons, impinge upon the body, the secondary electrons will be either fewer or greater in number than the primary electrons, being greater in number when the velocity is high. There is a critical velocity at which equilibrium between the number of primary and secondary electrons exists. The voltage applied to accelerate the beam from the first gun 11 for erasing purposes is sufficiently low so that electrons therein will impinge upon the dielectric 28 at a velocity below critical for the dielectric material. This voltage is furnished, for example, by a battery 40 which is connected at its positive side to the two anodes 15 and 17 of the first gun 11. The cathode 13 of this gun is connected to the movable element 41 of a three-position, single pole switch 42 of which one terminal 43 is the "erase" terminal. The erase terminal is connected to a movable tap 44 on the battery 40, which tap is adjusted to choose the required accelerating potential for the erase beam. Erasure is effected by operating the switch 42 to the erase position and scanning the beam from the first gun 11 repeatedly over the dielectric 28 of the storage screen 26 until a sufficiently uniform negative charge is placed thereon. The negative charge that results will

approach that of the cathode 13 with respect to the applied potential accelerating the erase beam. It is desirable to charge the dielectric side 28 of the storage screen 26 to a uniform negative potential of approximately 50 volts with respect to the collector electrode 35.

Writing

It will be assumed that the dielectric side of the storage screen 26 is charged to a uniform negative potential of the order of 50 volts with respect to the collector 35. Writing is accomplished by scanning the dielectric side of the screen 26 with a moderately high velocity electron beam, the velocity of which is sufficient so that the beam, when striking the dielectric 28, generates secondary electrons greater in number than the primary electrons. With such a velocity, the number of secondary electrons leaving an area under the beam will be greater than the number arriving, so that the area will become charged in a positive direction in proportion to the number of primary electrons striking the area. The secondary electrons will go to the collector 35 and anode coating 17 of the tube. Primary electrons passing through the screen 26 will be collected by the anode coating 25 of the second gun 12. The storage screen 26 is maintained positive in potential with respect to the anode coatings 17 and 25, and the collector 35 is maintained positive with respect to the screen. By the action of scanning and modulation of the writing beam intensity, a charge pattern is placed upon the dielectric surface 28 varying in intensity in accordance with the modulation. When the writing beam is cut off, the charge pattern remains, as there is no source of electrons to remove the charge.

The various required potentials can be furnished by any suitable means, for example, the battery 40 furnishes the accelerating potential for the writing beam when the full voltage thereof is applied between the cathode 13 and the high voltage anode 17. To this end the switch 42 is provided with a second selection terminal 46 which is connected to the negative end of the battery 40, and is employed as the "write" terminal of the switch. For writing, the switch 42 is operated to the write position. The screen 26 is made more positive than the anode coating 17 by a second battery 47, and the collector 35 is made more positive than the screen 26 by a third battery 48. Modulation of the intensity of the beam of the first gun 11 during writing is accomplished by means of a write input circuit 50, shown in block form, connected between the cathode 13 and the control grid 14 of the gun. A bias battery 51 provides an initial negative bias which is overcome or aided by the write input circuit to modulate the beam.

Reading

Once a charge pattern is placed upon the dielectric 28 of the screen 26, it can be read by scanning the uninsulated side 27 of the screen with an electron beam. The reading beam is furnished by the second gun 12 and can be arranged to provide a high voltage or low voltage beam, either above or below the critical velocity potential for the metal 27, as desired. If a high voltage beam is employed, those electrons which pass through the screen, shown more clearly in Fig. 2, travel at sufficiently high velocity to be collected by the coating anode 17 of the first

gun 11, while those which impinge upon the metal 27 cause the emission of secondary electrons. The metal 27 is connected in a circuit with the gun 12, so that no change in potential of the metal occurs thereby. The metal 27 of the screen 26 is maintained positive with relation to the anode coating 25 of the second gun 12, and the collector electrode 35 is maintained positive with respect to the metal 27 of the screen 26. Accordingly, the secondary electrons are attracted to the collector electrode 35 rather than to the anode coating 25 of the second gun 12. The charge existing around each of the holes 30 by virtue of the charge pattern on the dielectric 28 governs the number of secondary electrons that pass through each hole 30 to the collector electrode 35. Recalling that the dielectric 28 was originally charged to a potential approximately 50 volts negative with respect to the collector 35, it will be appreciated that with properly selected potential differences between the anode coating 25, the metal 27, and the collector 35, this charge in itself can be sufficient to prevent the passage of any secondary electrons through the holes 30. Thus the presence of positive charges in varying numbers around the various holes 30 governs the passage of secondary electrons through the holes 30 to the collector 35 in accordance with the amount of such charge. This, in turn, is in accordance with the modulation placed upon the writing beam by the write input circuit 50. The current that flows in this manner to the collector 35 flows also through a load resistor 53, across which the output signal is taken. The reading beam is scanned by the deflection coil system 24 of the second gun 12.

A suitable potential for accelerating the reading beam is provided by a battery 55 which is connected between the cathode 21 and the anodes 23 and 25 of the second gun 12 by a read switch 56 of the single-pole, double-throw variety. A suitable bias potential for the control grid 22 is furnished by a bias battery 57. The screen metal 27 is made positive with respect to the anode 25 of the second gun 12 by means of a suitable battery 58. The battery 48 which is connected between the screen metal 27 and the collector 35, which is used in the write circuit, is also used in the read circuit. The read switch 55 has an off position at which it is operated during writing and erasing. The write switch 42 has a third terminal 45 at which it is operated to store an image, which is then available to be read when desired.

By lowering the potential of the battery 55 below the value required to provide the electrons in the beam of the second gun 12 with critical velocity or above, a slow beam is provided. With this beam, those electrons which strike the metal 27 are absorbed by the screen 26 and returned to the cathode 21. Those electrons which tend to pass through the holes 30 are influenced at each hole by the charge pattern existing around the hole on the dielectric 28, so that the number of primary electrons passing through each hole varies in accordance with this charge pattern. Since the collector electrode 35 is the most positive element in the tube, the slow electrons are attracted to it and provide the output current in the resistor 53.

The dielectric material 28 may be any suitable dielectric material which can be placed upon the perforated plate 27 without completely filling the holes 30. Since, as has been pointed out

above, the dielectric material will, in practice, almost always tend at least partly to clog the holes, the metal plate 27 should be constructed initially with the largest practicable holes 30 to minimize the effect of such clogging. Satisfactory results have been obtained with calcium fluoride, barium fluoride, and lithium fluoride as dielectric materials, as well as magnesium oxide and calcium tungstate. The fluorides may be coated on the metal plate 27 by evaporation in a vacuum, calcium tungstate cataphoretically, and magnesium oxide by smoke precipitation inside an enclosed chimney. These procedures have been found to yield uniform coatings without too seriously reducing the hole size.

Performance tests made with storage screens constructed as set forth above have yielded the following information. If a stored image be read at the rate of 30 frames per second, the 20 scanning thereof being performed as in television, an image stored on a magnesium oxide screen will be found to persist for a time greater than ten minutes which corresponds to the retention of a stored signal for more than 18,000 25 readings. The same stored signal is retained for more than sixteen hours with the reading beam turned off. Under similar reading circumstances, a calcium fluoride screen was found to have a holding time greater than fifteen minutes, a 30 lithium fluoride screen not more than fifteen minutes, and a barium fluoride screen less than one-tenth of a second.

The resolving power of the foregoing screens in a tube of the present invention is found to be 35 substantially higher than that of prior known storage tubes. The resolving power of tubes of the invention was measured by writing an image made up of a series or group of dot elements on the storage surface and reading out the stored 40 image on a monitor. The number of dots per inch placed upon the storage screen by the writing beam was made initially few, and increased for successive writings until further increase showed a noticeable deterioration of the monitor image. With the magnesium oxide dielectric coating, the resolving power for read-out was measured in this way to be forty dots per inch on the storage screen. Using a writing beam which is 0.020 inch in diameter, it is possible to 45 write fifty dots per inch on the storage screen; that is, the electron spot size is fifty dots per inch. Therefore, the resolving power for read-out with the magnesium oxide screen is 80 per cent of the theoretical maximum permitted by 50 the reading electron gun. Similar tests showed that the calcium fluoride screen was 58 per cent efficient in this manner and the lithium fluoride screen 74 per cent efficient.

The writing speed that can be obtained with 55 storage screens constructed as set forth above was measured by means of a sine wave oscillator applied to deflect the writing beam in one direction and a single synchronized pulse to deflect the writing beam at right angles thereto. 60 The resulting trace was then examined by reading out on the monitor. The oscillation frequency or amplitude, or both, were increased between successive writings (with erasure between writings) until the trace showed indications of 65 thinning at the center. The writing speed at the center of the trace for this condition is taken as the maximum or saturation writing speed for the tube. Increase in writing speed beyond this point causes a dimmer trace rather than a disappearance of the trace, for the reason that in the tubes 70

of this invention the stored image has a continuous dynamic range. In this manner a saturation writing speed of 0.78 kilometer per second was measured for a 3.2 microampere beam current, using a magnesium oxide screen. The critical potential for this screen was estimated to be 75 volts. The writing speed of calcium fluoride and lithium fluoride screens was found to be less than this value.

Referring now to Fig. 3, another tube constructed in accordance with the invention is there shown, wherein reading and writing are accomplished with one and the same electron gun, while erasure is accomplished by a second flood gun, the beam of which does not have to be scanned. This tube comprises an envelope 60, of glass or the like, having in the right-hand end a reading and writing gun 61, and in the left-hand end an erasing gun 62. The reading and writing gun 61 is provided with deflection coil means 63 and a coated anode 64 inside the envelope 60 in the right-hand portion thereof. The coated anode 64 is provided with a terminal 65 imbedded in the glass of the envelope and in electrical contact with the anode 64. This terminal 65 is conveniently termed a "button terminal" because of its button-like appearance. The storage screen (not shown) is mounted in a ring 67 which is supported upon studs 68 and 69, of which the latter is electrically connected to a button terminal 70, which is, in turn, mounted in and through the envelope 60. The stud 69 has fastened thereto an insulation bead 72, while the other stud 68 has fastened thereto a second insulating bead 73. A second ring 74, having two mounting studs 75 and 76, is supported in the beads 72 and 73 by these studs in parallel relation to the first ring 67. The second stud 76 makes electrical contact with a button terminal 78 mounted in and through the envelope 60 in approximately diametric opposition to the button terminal 70 of the storage screen ring 67. A metallic screen 80 of the order of 100 mesh, 85 per cent open, is stretched tightly across the opening in the second ring 74, nearest the first ring 67. The storage screen which is mounted in the first ring 67 has its dielectric surface facing toward the metallic screen 80.

The flood gun 62 includes a cathode 82, a control grid 83, and an accelerating anode 84, having terminals 85, 86 and 87 passing through the left-hand wall 88 of the tube for the purpose of making electrical connections thereto. This gun may be of the kind shown and described in pending application, Serial No. 775,291, filed September 20, 1947. A coated anode 90 is provided for this gun on the inside of the envelope 60 in the left-hand portion thereof, this anode having a button terminal 91 mounted on the wall of the envelope. A collector electrode 92, annular in form like the collector electrode 35 in Fig. 1, is coated inside the envelope 60 between the erasing gun, coated anode 90, and the metallic screen 80. This collector electrode is likewise provided with an electrical connection in the form of a button terminal 93.

The tube shown in Fig. 3 can be erased, written upon, and read in similar fashion to that shown in Fig. 1.

Erasing

For erasing the storage surface of the screen 26, the circuit shown in Fig. 4 is suitable. A battery 95 is connected at its negative terminal to the cathode 82 of the erasing gun 62, and at

its positive terminal to the coated anode 90, the collector electrode 92, and the metallic screen 80 together. A variable tap 96 on the battery 95 is connected to the metallic screen 27 of the storage screen 26. The potential furnished by the battery 95 is sufficient to accelerate electrons toward the storage surface 28 with a somewhat high voltage, which is reduced to a voltage below the critical value by the potential furnished to the metal 27 of the storage screen 26 via the tap 96 on the battery 95, whereby the metal 27 is made negative with respect to the metallic screen 80, collector electrode 92, and coated anode 90. The beam from the electron gun 62 is a broad beam covering the entire storage surface 28, and imparts electrons to the storage surface until the charge thereon closely approaches the potential of the cathode 82. This action is similar to the erasing action described above in connection with Fig. 1.

Writing

The circuit shown in Fig. 5 is suitable for use in writing. A battery 97 is connected at its negative end to the cathode 98 of the reading and writing gun 61, and at its positive end to the coated anode 64 of said gun and the metal 27 of the storage screen 26 together. The potential furnished by the battery 97 is above the critical voltage for the dielectric material 28. The metallic screen 80 and the collector electrode 92 are made negative with respect to the cathode 98 by means of an auxiliary battery 101. A bias battery 102 is connected between the cathode 98 and the control grid 99 of the reading and writing gun 61, via the write input circuit 58. Deflection coil means 103 serve to deflect the beam 104 furnished by the gun 61, and thereby scan it over the storage screen 26. No connections are made to the erase gun or its coated anode 90 in Fig. 5. The metallic screen 80 is sufficiently negative with respect to the metal 27 of the storage screen 26 so that electrons of the beam 104, which pass through apertures 30 in the storage screen 26, are turned back and strike the dielectric material 28. For this reason, the metallic screen 80 is termed an "electron mirror."

Referring now to Fig. 7, the operation of the electron mirror will be explained in detail. In Fig. 7, only those parts which are necessary to explain the action of the electron mirror are shown, and these are shown greatly enlarged and in simplified form. However, the parts shown bear the same reference characters as the corresponding parts in Fig. 5. The path of a single electron passing from the cathode 98 through a hole 30 in the storage screen 26 is shown by a dashed line 106. The electron passes through a hole 30 and is carried by its momentum toward the electron mirror 80, which, however, exerts a retarding force upon the moving electron. Located between the storage screen 26 and the electron mirror 80 there is a plane of zero potential, represented by a dashed line A—A, at which the moving electron is stopped and turned about, and accelerated back towards the storage screen 26. The path of the electron, after entering the region between the storage screen 26 and the electron mirror 80, is very much like the trajectory of a projectile being hurled through the earth's atmosphere from one point on the earth to another with constant horizontal velocity and an initial upward velocity V_0 which is thereafter reduced to zero and reversed by the constant force of

gravity. The electron then strikes the dielectric 28 at a point B with a velocity above critical for the dielectric, and causes secondary electrons to emerge. Since the velocity of the primary electron upon striking is greater than the critical velocity, two secondary electron paths are shown to indicate more secondary electrons than primary electrons as a result of the striking. One secondary electron path 107 is shown in dotted line, while the other, 108, is a dot-dashed line. The secondary electrons are repelled by the electron mirror 80 and attracted by the metal 27 of the storage screen 26 and by the coated anode 64 of the read-write gun 61. As a result, the point B at which the primary electron struck the dielectric material 28 becomes more positive, as happens in the operation described above in connection with Fig. 1. It will be appreciated that writing has been accomplished by scanning the dielectric side of the storage screen 26 with a writing beam, just as is done in Fig. 1. However, the writing gun is located on the conductive side of the storage screen 26, and the beam is caused to reach the dielectric side by means of an electron mirror 80. Secondary electrons, which are emitted from the conductive side 27 of the storage screen 26, are captured by either the conductive metal 27 or the coated anode 64. By this construction, the same gun 61 can be used for writing as well as for reading.

Reading

The reading function of the tube of Fig. 3 can be performed with the circuit shown in Fig. 6. 35 This circuit closely resembles that of Fig. 1 for reading. A battery 111 is connected at its negative end to the cathode 98 of the read-write gun 61, and at its positive end to the electron mirror 80 and the two coated anodes 64 and 90 to thereby produce a beam 112 of any velocity desired, the velocity being governed by the voltage of the battery. The metal 27 of the storage screen 26 is made more positive than the electron mirror 80 and the two coated anodes 90 and 64 by means of a battery 113, while the collector electrode 92 is made still more positive by means of still another battery 114. The last battery 114 is connected at its negative terminal to the metal 27 of the screen electrode 26 and at its positive terminal to the collector electrode 92 via a resistor 115. The output signal upon reading is taken across this resistor.

As has been mentioned above, reading of the charge pattern can be accomplished in two ways, either by direct modulation of the electron beam 112 with the charge pattern, or by modulation of a cloud of secondary electrons created by the beam 112 at the storage screen 26. Primary electrons which strike the conductive metal 27 cause the emission of secondary electrons therefrom, which are now attracted to the collector electrode 92. The flow of secondary electrons to the collector electrode 92 through the holes 30 is governed by the potential of the electron mirror 80, which is not sufficiently great to cut off their flow, and by the charge on the dielectric 28 at the hole 30 through which a particular electron seeks to pass. The more positive the stored charge is, the greater will be the flow of secondary electrons through a particular hole 30 to the collector electrode 92. Thus, as in Fig. 1, with a reading beam of constant intensity and under the action of scanning, controlled by the deflection coil means 103, a current flows in the resistor 115

in accordance with the charge pattern on the storage screen 26.

When electrons of the beam 112 approach the screen 26 at sufficiently low velocity so that the charge pattern can have a modulating effect on them, primary electrons passing through the holes 30 in the storage screen 26 are modulated or governed in quantity in the same manner as are secondary electrons as described immediately above.

Referring now to Fig. 8, an embodiment of the invention is there shown wherein a single gun 117 is employed for reading, writing, and erasing. This tube employs a storage screen and metallic screen assembly similar in many respects to that shown in Fig. 3. Accordingly, like parts of this assembly have like reference characters in both Figs. 3 and 8. However, the metallic screen 80 is nearer to the gun 117 than is the ring 67 of the storage screen 26. The dielectric side of the storage screen 26 faces away from the gun 117, as is indicated in Figs. 9 and 10. A coated anode 119 is provided inside the envelope 120, being disposed between the metallic screen 80 and the gun 117. Deflection coil means 118 are provided for the gun. As will be explained below, the metallic screen 80 is employed as an element of the anode 119 in the present embodiment, and not as an electron mirror. In its place, a coated electron mirror 121 is provided on the interior of the wall of the tube opposite the end of the gun 117. Button terminals 122 and 123 are provided for the coated electron mirror 121 and the coated anode 119, respectively.

Erasing

Erasing in the embodiment of Fig. 8 is accomplished in the following manner. As shown in Fig. 9, a battery 126 is connected at its negative terminal to the cathode 127 of the gun 117, and at its positive terminal to the metallic screen 80 and the coated anode 119 together. A movable tap 125 on the battery 126 is connected to the metal 27 of the storage screen 26. A second battery 124 is connected at its positive terminal to the cathode 127 and at its negative terminal to the electron mirror 121. The beam furnished by the gun 117 is provided with an initial potential by the battery 126, which is above critical for the dielectric material 28, but which is reduced below critical by setting the movable tap 125 sufficiently close to the negative terminal of the battery 126. With the proper setting, electrons, traveling at below the critical velocity for the dielectric material 28, enter the region between the storage screen 26 and the electron mirror 121, are turned about, and strike the dielectric material 28 at a voltage below critical, thereby imparting a negative charge to the dielectric material. By suitable scanning, this negative charge is made uniform throughout, and the storage screen 26 is thereby erased to a uniform negative potential level.

Writing

Writing is accomplished with the circuit of Fig. 9, with the sole change that the tap 125 is moved sufficiently near the positive terminal of the battery 126, so that electrons which enter the region between the storage screen 26 and the electron mirror 121 are turned about and strike the dielectric material 28 with a voltage greater than critical. Secondary electrons,

which are thereby emitted, are attracted by the metallic screen 80 and the coated anode 119. The function of the metallic screen 80 in this case is to provide a uniform attracting field parallel to the storage screen 26, which is not provided by the coated anode 119 alone. Secondary electrons which are emitted by the striking of the beam against the metal 27 are likewise attracted by the metallic screen 80 and the coated anode 119. In this manner, writing produces a pattern of positive charges as in the other embodiments of the invention.

Reading

Reading is accomplished with a circuit like that shown in Fig. 10. A battery 130 is connected at its negative terminal to the cathode 127, and at its positive terminal to the electron mirror 121, via a load resistor 135, the electron mirror in this case functioning as a collector electrode. The metallic screen 80 and the coated anode 119 are together connected to a movable tap 132 on the battery 130. The metal 27 of the storage screen 26 is connected to a second movable tap 131 on the battery 130, which is maintained nearer the negative end of the battery than the first tap 132. The potential for accelerating the reading beam is determined by the setting of the first tap 132. The setting of the second tap 131 determines a deceleration potential to be applied to the beam. It is preferable to employ a fast beam initially in the interests of good resolving power, and to decelerate this beam at the storage screen in order that the charge pattern on the storage screen may control the flow therethrough of slow electrons to the collector 121. The current in the collector 121 flows through the resistor 135 across which the output is taken.

The foregoing considerations of the operation of the various embodiments of the invention have been confined to erasure of the type which produces negative charge, and writing of the type which produces positive charge. It is possible, by sufficiently accelerating the erasing beam to provide erasure which produces a positive charge. In this case in Fig. 1, secondary electrons produced by the first gun 11 from the dielectric material 28 would be collected by the coated anode 17 and by the collector anode 35. Thereafter, writing with a beam of lower velocity than critical would add charges to the screen and produce a negative charge pattern. The charge pattern on the storage screen 26 would then operate upon a reading beam in the same manner as described above, producing, however, an image which is photographically negative with respect to the image produced when writing is positive on a negative screen.

It will be appreciated by those skilled in the art that similar operation of the other embodiments of the invention can be had. For example, in Fig. 4, if the electrons from the gun 62 are sufficiently fast, secondary electrons will emerge from the dielectric 28 and will be collected at the positive terminal of the battery 95, thereby charging the dielectric 28 positively for erasure purposes. Then in Fig. 5, if writing is with a sufficiently slow beam, the electrons which are turned about by the electron mirror 80 will accumulate on the dielectric 28 and produce a negative charge pattern.

In the embodiments of Figs. 3 and 8, it is possible to employ element-by-element tracking of

the recorded charge pattern, for the same gun is used in each embodiment to provide both the writing and reading electron beams. With tracking of this kind, it is further possible to return to a particular portion of the recorded charge pattern on the screen 26 to sample the information stored therein, without the necessity of examining the entire charge pattern.

If it is desired to enable an observer to view a charge pattern that is being read, the coated electrode 121 in the embodiment of Fig. 8 may be made in two layers, as shown in Fig. 11. One layer is a thin film 141 of platinum in contact with the envelope 120 and the other layer 142 is a fluorescent material. The platinum film 141 is normally evaporated onto the envelope end wall and is maintained sufficiently thin so that it is only about 20 per cent opaque, while the fluorescent material 142 is deposited on the platinum. The reading beam impinging on the fluorescent material will then cause visible emission therefrom, which will be visible through the platinum film. Electrons will penetrate the fluorescent film and arrive at the platinum film which then functions as a collector electrode. The platinum film also functions as an electron mirror in the circuit of Fig. 9.

Many other variations and modifications will occur to those skilled in the art, and it is therefore intended that the claims that follow shall not be limited by the details of any of the embodiments shown and described herein, but only by the prior art.

What is claimed is:

1. In an electronic charge storage device, a perforated storage target having an electrically conductive side and a dielectric side, means providing an electron beam for scanning said dielectric side, to produce a charge pattern thereon, and means providing an electron beam to scan said conductive side.

2. In an electronic charge storage device, a perforated storage target having an electrically conductive side and a dielectric side, means providing an electron beam for scanning said dielectric side, means for modulating said beam during scanning, and means providing an electron beam to scan said conductive side.

3. In an electronic charge storage device, a charge storage target having an electrically conductive side and a dielectric side, a plurality of apertures through said target substantially uniformly distributed over the surface thereof, means providing an electron beam for scanning said dielectric side, said beam being of sufficient width simultaneously to include several of said apertures, and means providing an electron beam to scan said conductive side.

4. In an electronic charge storage device, a charge storage target having an electrically conductive side and a dielectric side, a plurality of apertures through said target substantially uniformly distributed over the surface thereof, means providing an electron beam for scanning said dielectric side, said beam being of sufficient width simultaneously to include several of said apertures, and means providing an electron beam having a width of the same order of magnitude as the first-mentioned beam to scan said conductive side.

5. In an electronic charge storage device, a perforated storage target having an electrically conductive side and a dielectric side, means providing an electron beam for scanning said conductive side, and means to cause an electron

of said beam which passes through said target to alter its course and impinge upon said dielectric side.

6. In an electronic charge storage device, a perforated storage target having an electrically conductive side and a dielectric side, means providing an electron beam for scanning said conductive side, and means to cause an electron of said beam which passes through said target substantially to reverse its course and impinge upon said dielectric side near the region of passing through.

7. In an electronic charge storage device, a perforated storage target having an electrically conductive side and a dielectric side, means providing an electron beam for scanning said dielectric side, to produce a charge pattern thereon, means providing an electron beam to scan said conductive side, and means for providing a uniform charge of a desired polarity to said dielectric side.

8. In an electronic charge storage device, a perforated storage target having an electrically conductive side and a dielectric side, means providing an electron beam for scanning said dielectric side, to produce a charge pattern thereon, means providing an electron beam to scan said conductive side, and means for scanning said dielectric side with an electron beam substantially uniformly over the entire area thereof.

9. In an electronic charge storage device, a perforated storage target having an electrically conductive side and a dielectric side, means providing an electron beam for scanning said dielectric side, to produce a charge pattern thereon, means providing an electron beam to scan said conductive side, and means providing a beam of electrons of sufficient width to cover substantially the entire area of said dielectric side.

10. In an electronic charge storage device, a perforated storage target having an electrically conductive side and a dielectric side, means for causing electrons to impinge on said dielectric side substantially uniformly throughout the area thereof, means providing an electron beam for scanning said dielectric side, and means providing an electron beam to scan said conductive side.

11. In an electronic charge storage device, a perforated storage target having an electrically conductive side and a dielectric side, means for causing electrons to impinge on said dielectric side substantially uniformly throughout the area thereof and with a velocity below the critical velocity for the dielectric material, means providing an electron beam with a velocity above said critical velocity for scanning said dielectric side, and means providing an electron beam to scan said conductive side.

12. In an electronic charge storage device, a perforated storage target having an electrically conductive side and a dielectric side, means for causing electrons to impinge on said dielectric side substantially uniformly throughout the area thereof and with a velocity on one side of the critical velocity for the dielectric material, means providing an electron beam with a velocity on the other side of said critical velocity for scanning said dielectric side, and means providing an electron beam to scan said conductive side.

13. An electronic charge storage device comprising a perforated storage target having an electrically conductive side and a dielectric side,

a first electron gun disposed to said conductive side, an a second electron gun disposed to said dielectric side, and an apertured electrically conductive planar member adapted to use as an electron mirror disposed between said second gun and said dielectric side.

14. An electronic charge storage device comprising a perforated storage target having an electrically conductive side and a dielectric side, an electron gun disposed to said conductive side, and an electron mirror disposed to said dielectric side.

15. An electronic charge storage device comprising a perforated storage target having an electrically conductive side and a dielectric side, an electron gun disposed to said conductive side, and a conductive plate lying in a plane parallel to that of said target to said dielectric side.

16. An electronic charge storage device comprising a perforated storage target having a conductive side and a dielectric side, a first electron gun disposed to said conductive side, a second electron gun disposed to said dielectric side, and a conductive screen interposed between said dielectric side and said second gun.

17. In an electronic charge storage device, a perforated storage target having an electrically conductive side and a dielectric side, means providing an electron beam for scanning said dielectric side, to produce a charge pattern thereon, means providing an electron beam to scan said conductive side, and output signal collector means disposed to said dielectric side.

18. An electronic charge storage device comprising a perforated storage target having an electrically conductive side and a dielectric side, an electron gun disposed to said conductive side, a planar conductive element disposed to said dielectric side parallel to said screen and of similar extent, and an annular electrode disposed between said conductive element and said target circumscribing but out of a direct path from said element to said target.

19. An electronic charge storage device comprising a perforated storage target having an electrically conductive side and a dielectric side, an electron gun disposed to said conductive side, and a conductive element disposed to said dielectric side, said conductive element including a fluorescent material.

20. An electronic charge storage device comprising a perforated storage target having an electrically conductive side and a dielectric side, an electron gun disposed to said conductive side, and a conductive element disposed to said dielectric side, said conductive element being in the form of a layer of conductive material and a layer of fluorescent material.

21. In an electronic charge storage device, a perforated storage target having an electrically conductive side and a dielectric side, means providing an electron beam adapted to scan said conductive side, means to cause an electron of said beam which passes through said target to alter its course and impinge upon said dielectric side, and means on said dielectric side adapted to provide a second beam of electrons of sufficient width to cover substantially the entire area of said dielectric side.

22. An electronic charge storage device comprising a perforated storage target having a conductive side and a dielectric side, a first electron gun disposed to said conductive side and arranged to provide a narrow electron beam, means for scanning said beam over said con-

ductive side, a second electron gun disposed to said dielectric side and arranged to provide a beam of breadth sufficient to cover all elements of said dielectric side simultaneously with electrons, and an electrically conductive screen interposed between said second gun and said dielectric side.
